UNITED STATES PATENT OFFICE

ADOLPH R. KUNZ, OF PHOENIX, ARIZONA

CENTRIFUGAL AIR OR GAS INJECTOR

Application filed April 4, 1933. Serial No. 664,438.

The present invention relates to new and useful improvements in air or gas injectors of the centrifugal type and has for one of its important objects to provide, in a manner as hereinafter set forth, a device of this character which comprises a novel construction of rotary impeller through the medium of which a suitable liquid is utilized for actuating the air, gas or other fluid.

10 Other objects of the invention are to provide a centrifugal injector of the aforementioned character which will be simple in construction, strong, durable, highly efficient and reliable in operation, compact, 15 light in weight and which may be manufactured and operated at low cost.

All of the foregoing and still further objects and advantages of the invention will become apparent from a study of the following specification, taken in connection with the accompanying drawings wherein like characters of reference designate corresponding parts throughout the several views, and wherein:

25 Figure 1 is a view in vertical longitudinal section through an injector constructed in accordance with the present invention.

Figure 2 is a fragmentary view in horizontal section through a portion of the housing, showing a portion of the impeller.

30 Figure 3 is a fragmentary view, partially in side elevation and partially in vertical section, showing a portion of the impeller.

Figure 4 is a sectional view, taken substantially on the line 4-4 of Figure 3.

35 Figure 5 is a sectional view, taken substantially on the line 5-5 of Figure 3.

Referring now to the drawings in detail, it will be seen that the embodiment of the invention which has been illustrated comprises a housing which is designated generally by the reference numeral 1, said housing being formed to provide an annular 40 chamber 2 having an outlet 3 and including a pair of complementary half sections 4 which are detachably secured together, as at 45. Projecting from opposite sides of the housing 1 are centrally located liquid inlets 6 having ports 7 therein. The housing 1 may

be mounted on any suitable supporting means.

Connected to the inlets 6 of the housing 1 are liquid reservoirs 8, only one of which has been shown. The reference numeral 9 designates generally a centrifugal impeller which is mounted for rotation in the housing 1. The impeller 9 is fixed on one end portion of a drive shaft 10 which extends rotatably into the housing 1 through one of the sections 4 thereof, said drive shaft passing through the liquid reservoir 8 on that side of the housing. Any suitable means may be employed for driving the shaft 10.

The impeller 9 includes a pair of side abutting disks 11 which are secured together in any suitable manner, said disks including hub portions 12. One of the hub portions 12 receives the drive shaft 10 while the other of said hub portions has connected thereto for rotation with the impeller 9 an air or gas inlet tube 13 which extends rotatably through the reservoir 8 on that side of the housing 1. The outer end portion of the rotary tube 11 is journaled in a stationary intake 14 which is mounted on the adjacent reservoir 8. The reference numeral 15 designates a suitable check valve on the inlet end of the intake pipe 14. A suitable packing 16 is provided for preventing leakage around the rotary air intake tube 13 from the adjacent liquid reservoir 8.

The impeller 9 further includes substantially semi-lanceolate blades or vanes 17 which are mounted in staggered relation to each other on the outer sides of the disks 11. The vanes 17 are arranged in a manner to define radial passages 18, as illustrated to advantage in Figure 3 of the drawings. Air chambers 19 are provided in the inner portions of the vanes 17, said chambers communicating with the passages 18 through diverging ports 20. The outer portions of the vanes 17 have chambers 21 therein. Radial passages 22 are formed in the impeller 9, said passages communicating with the tube 13 for receiving air therefrom and also communicating, at their outer ends, with the chambers 19 for the discharge of the air thereinto.

The outlet 3 of the housing 1 is to be connected by suitable conduits to a receiving tank (not shown) into which the mixed liquid and air or gas is discharged. Liquid 5 is supplied to the reservoirs 8 from this receiving tank through suitable pipes 23 which are connected to the bottom or a lower portion of said receiving tank.

Briefly, the operation of the injector is as 10 follows:—

When the impeller 9 is rotated the liquid 15 is thrown by centrifugal force outwardly into the annular chamber 2. As the liquid rushes past the ports 20 through the passages 18, air will be drawn from the atmosphere through the inlet members 13 and 14 and be discharged also into the chamber 2. Of course, if the inlet members 13 and 14 20 communicate with a supply of gas other than the atmosphere, this particular gas will be discharged into the chamber 2. The liquid and air or other gas then pass from the chamber 2 through the outlet 3 to the aforementioned receiving tank where they separate, the liquid, of course, settling in the 25 bottom of said receiving tank. The air or other gas may then be withdrawn from the receiving tank as desired and in any suitable manner. The liquid returns to the reservoirs 8 through the pipes 23 to be used again.

It is believed that the many advantages 30 of an injector constructed in accordance with the present invention will be readily understood, and although the preferred embodiment of the invention is as illustrated and described, it is to be understood that changes 35 in the details of construction and in the combination and arrangement of parts may 40 be resorted to which will fall within the scope of the invention as claimed.

What is claimed is:—

1. A centrifugal injector comprising a

housing having an annular chamber therein and further having an outlet passage communicating with the chamber, means for supplying a liquid to the housing, an impeller rotatably mounted in the housing, said 70 impeller having radial passages, therein, means for supplying a fluid to the passages, said impeller including laterally projecting vanes spaced from each other and defining passages therebetween for the liquid, said 75 vanes having ports therein communicating with the first and second named passages.

2. A centrifugal fluid injector comprising a housing having an annular chamber therein, means for introducing a liquid into the housing, an impeller rotatably mounted in the housing, said impeller having radial air 80 passages therein and including laterally projecting, spaced vanes defining radial passages communicating with the chamber, said 85 vanes having chambers therein communicating with the first named passages and further having diverging ports therein communicating with the second named passages and with the second named chambers, and 90 means for conducting the fluid into the impeller.

3. A centrifugal injector comprising a housing having an annular chamber therein and further having an outlet passage communicating with the chamber, a reservoir connected with the housing for supplying a liquid thereto, a drive shaft extending rotatably into the housing, an impeller fixed 100 on the shaft and operable in the housing, said impeller having air passages therein, an air inlet pipe extending rotatably through the reservoir and connected to the impeller for the introduction of air into the passages, and means for supplying liquid to the reservoir. 105
